UNITED STATES PATENT OFFICE.

WILLIAM S. GRAFF BAKER, OF LONDON, ENGLAND, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

1,313,977.

Specification of Letters Patent. Patented Aug. 26, 1919.

Application filed August 18, 1917. Serial No. 187,021.

To all whom it may concern:

Be it known that I, WILLIAM SEBASTIAN GRAFF BAKER, a citizen of the United States of America, residing at London, in the 5 county of Middlesex, England, have invented certain new and useful Improvements in Railway-Traffic-Controlling Apparatus, of which the following is a specification.

My invention relates to railway traffic 10 controlling apparatus and particularly to block signaling systems.

I will describe one form of block signaling system embodying my invention and will then point out the novel features thereof in 15 claims.

The accompanying drawing is a view showing diagrammatically one form of block signaling system embodying my invention.

20 Referring to the drawing in detail, my invention in this embodiment is here shown applied to a single section of railway track B over which traffic normally moves in the direction indicated by the arrow. This section B is only one of a plurality of such sections constituting a railway wherein the sections are defined and insulated from adjoining sections by suitable means, such, for example, as insulated joints 10—10, etc.

25 T designates a transformer, the primary of which is connected to a generator (not shown) while the secondary is connected across the track rails of the section B adjacent the entrance end of such section by 30 means of leads 11 and 12. Connected in with the lead 12 and in series with the secondary of the transformer T is a signal designated R, which, as here shown, is an electric lamp. A second signal G, which is

35 also in the form of an electric lamp, is connected across the track rails of the section B adjacent the exit end thereof by means of wires 13 and 14, and is preferably located at the entrance end of the section and in close 40 proximity to the lamp R. The lamps R and G are provided with red and green lenses or globes, respectively, so that when illuminated they will indicate "stop" and "proceed" respectively.

45 50 From the foregoing arrangement it will be seen that a track circuit is formed wherein the lamps R and G are permanently connected in series with each other and with the secondary of transformer T, the track rails 55 of section B serving to conduct current to

and from the lamp G. The parts of this track circuit are so proportioned that when the section B is unoccupied by a train or car, lamp R is extinguished and lamp G is illuminated, as shown in the drawing, 60 whereas when the section is occupied lamp G is extinguished and lamp R is illuminated. I obtain this operation of the signals R and G by making the resistance of the lamp G higher than the resistance of lamp R, al- 65 though I do not limit myself to this particular manner of obtaining this operation. As the lamp R has a lower resistance than lamp G, it is obvious that with the transformer supplying current at a constant and 70 predetermined voltage, and the resistances of the lamps properly proportioned with relation to such voltage, when the circuit is intact, as shown in the drawing, the current will be insufficient to illuminate the lamp R 75 but sufficient to illuminate the lamp G. However, should the lamp G be short-circuited by a low resistance shunt, such as the wheels and axles of a train or car, lamp G is extinguished, and since the resistance 80 thereof is then removed from the circuit, the current in the remainder of the circuit is increased and is sufficient to illuminate the lamp R. In order to compensate for variation in the resistance between the track rails 85 of section B, for instance, in the case of a track exposed to climatic variations, a resistance X may be connected in shunt to the lamp R, as shown.

85 The operation of the signaling system is 90 as follows: When the section B is unoccupied, as shown in the drawing, only lamp G is illuminated, which, by virtue of its green lens indicates "proceed" to trains or cars approaching from the left. However, when 95 a train or car enters the section, the wheels and axles thereof constitute a low resistance shunt to lamp G whereby the latter is extinguished and the lamp R illuminated. With the lamp R illuminated, a "stop" indication 100 is given by virtue of the red lens, thus cautioning a following train or car from entering the occupied section. The lamp R is maintained illuminated so long as the train or car occupies the section, but upon leaving 105 the section the low resistance shunt is removed so that lamp G is again illuminated and lamp R extinguished. Thus the signaling system is restored to its normal condition 110 for operation by succeeding trains or cars.

It will be manifest from the foregoing that I have provided a railway signaling system in which operation of the signals is automatically performed without the employment of relays which have been essential elements in railway signaling systems with which I am familiar, thus producing a system having the desirable characteristics of simplicity, durability and efficiency.

10 Although I have herein shown only one form of signaling system embodying my invention, it is understood that various changes and modifications may be made therein within the scope of the appended 15 claims without departing from the spirit and scope of my invention.

Having thus described my invention, what I claim is:

1. A railway signaling system comprising 20 a section of railway track, a source of current connected across the track rails of said section at one end thereof, a lamp interposed between said section and source of current and connected in series with the latter, and 25 a second lamp connected across the track rails of said section at the other end thereof, said first-mentioned lamp having a lower resistance than the second lamp.

2. A railway signaling system comprising 30 a section of railway track, and a track circuit therefor including a source of current, a pair of lamps and the track rails of said section, said track rails being interposed between and connecting said lamps in series 35 with said source of current.

3. A railway signaling system comprising 35 a section of railway track, a track circuit therefor including a source of current and two signals having different resistances, said

track circuit being so arranged and proportioned that one or the other of said signals will be caused to give a visible indication according as the section is occupied or unoccupied.

4. A railway signaling system comprising 45 a section of railway track, a source of current connected across the rails of said section, a signal lamp included in the connection between one terminal of said source and one rail, and a second signal lamp connected 50 across the rails of said section.

5. A railway signaling system comprising a section of railway track, a track circuit therefor including a source of current and two electric lamps, the parts of said track 55 circuit being so proportioned that one of said lamps is extinguished and the other illuminated when said section is occupied, and that the first lamp is illuminated and the second extinguished when the section is 60 unoccupied.

6. A railway signaling system comprising a section of railway track, a source of current connected across the rails of said section, a signal lamp included in the connection between one terminal of said source and one rail, a resistance connected across the terminals of said lamp, and a second signal lamp connected across the rails of said section.

In testimony whereof, I have signed my name to this specification in the presence of two subscribing witnesses.

WILLIAM S. GRAFF BAKER.
